UNITED STATES PATENT OFFICE.

ALEXANDER HENDRY AND MALCOLM ALLAN HENDRY, OF GLASGOW SCOTLAND.

BELT FOR MACHINERY DRIVING.

Application filed September 23, 1919. Serial No. 325,614.

To all whom it may concern:

Be it known that we, ALEXANDER HENDRY and MALCOLM ALLAN HENDRY, belting manufacturers, subjects of the King of Great Britain and Ireland and the Isle of Man, of 5 252 Main Street, Bridgeton, Glasgow, Scotland, have invented new and useful Improvements in and relating to Belts for Machinery Driving, of which the following is 10 a specification.

This invention has reference to improvements in and relating to belts for machinery driving, where these are formed of parallel layers of leather or other suitable material 15 of laminated or like construction.

These belts as usually constructed have the exposed side surfaces of the outer layers of channel or like formation, and the stitching or attaching sewing at the centre part 20 is thus preserved, but when the belt gets worn by frictional action against the striking gear, or shifting belt forks, the centre part also gets ultimately attacked and to obviate or lessen this our present improvements 25 are designed.

This we accomplish by forming an unexposed surface of the second or next layer of a concave or like shape. This enables the adjacent or inner flat surface of the 30 outer layers to bear or abut against the secondary layers so that the frictional wearing surface of the striking gear or belt forks acts against the two outer side edges of these outside exposed layers, and the sewing or attaching stitching in the centre is thus preserved and the length of the wear of the belt prolonged.

By a modified arrangement, in some cases curved surfaces may be formed on the third 40 or more layers from each side of the laminated belt to give a like compensating action; and by a further modification both surfaces of each layer may be formed of a concave or like curved shape.

In some cases there may be an irregularity of concave grooves, that is the groove or curved surface may only be intermittently formed at spaced distances apart on two or 45 more of the strands, but the uniformity of curved surface action would be accomplished by the concavity achieved by the combination of the number of strands.

In order that our said invention and the manner of carrying the same into effect or 50 practice may be properly understood we

have hereunto appended one sheet of explanatory drawings in which:—

Figure 1 is a transverse sectional elevation of a laminated belt having the layers or strands constructed according to this invention and assembled in position but not secured together.

Figure 2 is a similar view but illustrates the layers secured together.

Figure 3 is an elevation of one of the 65 strands showing the longitudinal groove.

Figure 4 comprises sectional elevations of strands illustrating various forms of grooves.

Figure 5 comprises elevations of two 70 strands when the grooves are not continuous; but the grooves of the one strand are arranged in staggered relationship with the grooves of the other strand.

Figure 6 is an elevation similar to Figure 75 3, but illustrates one of the forms of strand shown in Figure 4.

Referring to these drawings:—In carrying the improvements of this invention into effect or practice a few of the strands (it 80 may be two, three or more) forming the laminated belt are made with longitudinal grooves.

As illustrated by Figure 1 the outer surfaces of the second, third and fourth outer 85 unexposed strands *a* are formed with longitudinal grooves *b* of a V or concave shape so that when the strands are bound together by the stitching *c* the strands *a* at each side of the belt assume the formation illustrated 90 by Figure 2.

The section 1 of Figure 4 illustrates one of the V or like shaped grooved strands of Figures 1 and 2.

The section 2 illustrates a strand with V 95 shaped grooves *b* on each side of the strand.

The section 3 illustrates a curved instead of a V shaped groove *b* on one side of the strand.

The section 4 illustrates a curved groove *b* 100 on each side of the strand.

The section 5 illustrates a double strand secured together by longitudinal stitching *d* and having a V shaped groove on one side.

The section 6 illustrates a double strand 105 secured together by longitudinal stitching *d* and having a curved groove on one side.

The section 7 illustrates the double strand of section 6 with the curved groove *b* on both sides of the strand.

Figure 6 is an elevation of the double section 6 or 7.

In Figure 5 the grooves are not continuous but then the strands are so assembled that the grooves are arranged in staggered relationship and the resultant effect is the same as when the grooves are continuous.

Having now particularly described and ascertained the nature of our said invention and in what manner the same is to be performed, we declare that what we claim is:

1. A belt for machinery driving comprising a plurality of strips of material arranged side by side and secured together, an unexposed surface of an inner strip in proximity to the outer strip having therein a groove extending longitudinally of the belt, substantially as and for the purpose set forth.
2. A belt for machinery driving comprising a plurality of strips of material arranged side by side and secured together, the outer unexposed surface of an inner layer in proximity to the outer strip having therein a groove extending longitudinally of the belt, substantially as and for the purpose set forth.
3. A belt for machinery driving comprising a plurality of strips of material arranged side by side and secured together, each of the unexposed surfaces of an inner strip in proximity to the outer strip having therein a groove extending longitudinally of the belt, substantially as and for the purpose set forth.
4. A belt for machinery driving comprising a plurality of strips of material arranged side by side and secured together, an unexposed surface of each of the strips next to the outermost strips having therein grooves extending longitudinally of the belt, substantially as and for the purpose set forth.
5. A belt for machinery driving comprising a plurality of strips of material arranged side by side and secured together, both of the unexposed surfaces of each of the strips lying next to the respective outermost strips having therein a groove extending longitudinally of the belt, substantially as and for the purpose set forth.

ing a plurality of strips of material arranged side by side and secured together, both of the unexposed surfaces of each of the strips lying next to the respective outermost strips having therein a groove extending longitudinally of the belt, substantially as and for the purpose set forth.

6. A belt for machinery driving comprising a plurality of strips of material arranged side by side and secured together, an unexposed surface of a plurality of inner layers in proximity to the outer strip having therein a series of spaced and substantially aligned grooves extending longitudinally of the belt, the grooves of the respective series being arranged in staggered relationship, substantially as and for the purpose set forth.

7. A belt for machinery driving comprising a plurality of strips of material arranged side by side and secured together, the unexposed surfaces of a plurality of inner strips in proximity to the outer strip having therein a series of spaced and substantially aligned grooves extending longitudinally of the belt, the grooves of the respective series being arranged in staggered relationship, substantially as and for the purpose set forth.

8. A belt for machinery driving comprising a plurality of strips of material arranged side by side and secured together, an unexposed surface of a plurality of strips next to the outermost strip having therein grooves extending longitudinally of the belt and bearing on the surface of the outer adjacent strip, substantially as and for the purpose set forth.
